UNITED STATES PATENT OFFICE.

ROSS M. G. PHILLIPS, OF WEST HAVEN, CONNECTICUT, ASSIGNOR TO THE SENTINEL AUTOMATIC GAS APPLIANCE CO., OF NEW HAVEN, CONNECTICUT, A CORPORATION.

DESIGN FOR A DIAL FOR AUTOMATIC COOK-STOVES.

45,916.

Specification for Design.

Patented June 9, 1914.

Application filed February 27, 1914. Serial No. 821,588. Term of patent 14 years.

To all whom it may concern:

Be it known that I, Ross M. G. PHILLIPS, a citizen of the United States, residing at West Haven, in the county of New Haven and State of Connecticut, have invented a new, original, and ornamental Design for a Dial for Automatic Cook-Stoves, of which the following is a specification, reference being had to the accompanying drawing, forming part thereof.

The figure is a face view of a dial for automatic cook stoves, showing my new design.

I claim:

The ornamental design for a dial for automatic cook stoves, as shown.

ROSS M. G. PHILLIPS.

Witnesses:

M. P. NICHOLS,
GEORGE D. SEYMOUR.
